UNITED STATES PATENT OFFICE

ROYDON E. HUNTER, OF DINUBA, CALIFORNIA

BROODER

Application filed July 30, 1930. Serial No. 471,835

This invention relates to brooders, one of the objects being to provide an inexpensive and efficient device of this character which can be operated at low cost and will keep the chicks warm and contented without danger of crowding and sweating.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings

Figure 1 is a central vertical section through the brooder.

Figure 2 is a plan view, a portion being broken away.

Referring to the figures by characters of reference, 1 designates the conical body of the brooder which is preferably formed of sheet metal. It has inner and outer walls 2 and 3 spaced apart to form a dead-air space 4, and at the apex of the body there is provided a ventilating opening 5. An annular apron 6 is provided at the lower edge of the body while connected to the upper portion thereof are chains 7 or other flexible devices whereby the brooder can be suspended with the body at any desired distance from the floor.

A screen 8 is connected to concentric reinforcing rings 9 and supported by the central portion of this screen is a shield plate 10. The screen, which is circular, is supported detachably in the lower portion of body 1 by any suitable means such as inclined studs 11 all but one of which extends under the margin of the screen. The other stud 11 can engage a retaining plate 12 held thereto by a nut 13. Thus by removing plate 12 the screen can be lowered and slipped off of the studs.

Tufts of feathers have been indicated at 14 and are connected to the screen 8 in any suitable manner. For example they can be tied

thereto by means of wires 15. The tufts extend below the apron 6 and form a continuous mass above which the screen is concealed.

In the space above the screen is supported a heating unit 16 which can be an ordinary incandescent lamp with a carbon filament.

In practice the brooder is suspended at the point of use so that the tufts of feathers will just touch the floor thereunder. An electric current is directed to the lamp and the heat thus generated will be sufficient to keep the feathers warm so as to afford ample protection for the chicks which will enter between the feathers and be protected thereby.

Should it be desired to separate the parts it would be necessary solely to detach plate 12 from the stud to which it is secured. The screen can then be withdrawn from body 1 and the studs 11 supporting the screen.

By forming the body with a dead-air space 70 within the double wall, the loss of heat through the wall is practically eliminated. The shield 10 deflects the heat from above those feathers at the center of the brooder and the apron 6 serves as a baffle to deflect 75 cold air which might otherwise tend to flow unhampered through the upper portions of the marginal feathers and the adjacent portion of the screen.

What is claimed is:

A brooder including a conical body having a dead-air space in the wall thereof and a ventilating opening at its apex, there being a depending annular apron at the margin of the body, downwardly converging spaced 80 studs within the body, a screen having its marginal portion insertible onto the studs, means engaging one of the studs for holding the screen upon all of the studs and encircled by the body, and feathers secured to and 85 depending from the screen to form a mass of substantially uniform density extending from the screen and below the body, said mass being arranged entirely across the lower surface of the screen.

In testimony that I claim the foregoing as my own, I have hereto affixed my signature.

ROYDON E. HUNTER.
